Attorney

UNITED STATES PATENT OFFICE.

ELLSWORTH NICCUM, OF KENT, WASHINGTON.

LADDER.

1,401,354.

Specification of Letters Patent. Patented Dec. 27, 1921.

Application filed March 15, 1920. Serial No. 366,002.

To all whom it may concern:

Be it known that I, ELLSWORTH NICCUM, a citizen of the United States, residing at Kent, in the county of King and State of Washington, have invented certain new and useful Improvements in Ladders; and I do hereby declare the following to be a full, clear, and exact description of the invention, such as will enable others skilled in the art 10 to which it appertains to make and use the same.

My invention relates to ladders and embodies improved features applicable to both extension and non-extension ladders.

15 It is my purpose to provide an improved construction for use in connection with extension ladders embodying a lower section and an upper movable section, which will automatically operate as the upper section 20 is elevated to secure the same against descent, and which is manually releasable at will to permit descent of the upper section of the ladder.

25 A further purpose of my invention is to provide an improved adjustable prop base for use in connection with either extension or non-extension ladders.

With the above and other purposes in view my invention consists in the details of 30 construction and in the arrangement and combination of parts to be hereinafter more particularly pointed out in the claims.

In describing my invention in detail reference will be had to the accompanying 35 drawings wherein like characters of reference denote corresponding parts in the several views, and in which—

Figure 1 is a front elevation of an extension ladder constructed in accordance with 40 my invention;

Fig. 2, a side view of same;

Fig. 3, a partial vertical section of the ladder showing the pawl carried by the upper movable section and which automatically 45 engages the rungs of the lower section to secure the upper movable section against descent;

Fig. 4, a perspective view of the connection between the props of the lower section 50 and the upper movable section which permits adjustment of the props in harmony with the adjustment of the ladder sections;

Fig. 5, a detail elevation of the adjustable prop base;

55 Fig. 6, a section on the line 6—6 of Fig. 5;

Fig. 7, a side elevation of a non-extensible

ladder embodying the adjustable prop base in a slightly modified form;

Fig. 8, a detail elevation of the prop base shown in Fig. 7; and

Fig. 9, a section on the line 9—9 of Fig. 8.

Referring to Figs. 1 to 6 inclusive of the drawings my improved ladder is shown as comprising a lower section A and an upper movable section B. The section A includes side members 10 and 11 connected by the usual rungs 12 and strengthened by tie rods 13 disposed directly beneath the rungs. Likewise the section B is formed of side members 14 and 15 connected by the usual rungs 16 and strengthened by tie rods 17 disposed directly beneath the rungs. The sections A and B are slidably secured together by means of keepers 18 and 19 secured respectively to the sections A and B. Secured to the lower ends of the side members 10 and 11 of the section A respectively are outwardly and downwardly inclined base beams 20 and these base beams are in turn connected with the side members 10 and 11 respectively adjacent the upper ends of the latter by means of braces 21. To secure the member B at a desired elevation with respect to the member A I pivotally mount on one of the tie rods 17 a U-shaped pawl 22 which, when the ladder is inclined to any extent, will swing to a position to overlie one of the rungs 12 of the prop A and in this way prevent descent of the member B. As the ladder member is elevated it will be apparent that the pawl 22 will ratchet over the rungs 12 and as it passes each rung it will swing to a position to engage the next lower rung 12 on the member A. This pawl 22 is provided with a handle 23 whereby it may be swung out of 85 overlying relation with the related rung 12 to permit descent of the upper section B. This handle also serves as a stop to limit inward movement of the pawl, said handle engaging a rung of the section B for that purpose.

The section A of the ladder has pivoted thereto a prop C formed of members 24 and 25 converging downwardly and connected at their lower ends by a spacing block 26. Secured to the front and rear of this spacing block 26 are plates 27 between the lower ends of which I pivotally mount a prop base 28. Secured to this base is an arcuate segment 29 provided with notches 30 in which is 105 adapted to be engaged and disengaged a pawl 31 pivoted to the prop member 24 and

controlled by a flexible connection 32 carried through a suitable guide 34 on the member 24. The arcuate segment 29 is held in proper relation to the prop members 24 and 25 by a guide plate 35 fixed on the prop member 25 and having a notch 36 in which the arcuate segment is engaged and travels during pivotal movement of the prop base 28.

10 It will be observed that when the prop base 28 is used the base beams 20 may be dispensed with as the base 28 will impart ample stability to the ladder. On the other hand, if desired, the prop base can be dispensed 15 with and the base beams 20 retained with still ample stability present for safe use of the ladder. It is believed desirable, however, to employ both of these elements in the ladder construction to secure the greatest 20 stability, especially in cases where the ladder is extended to great heights.

Pivotedly secured to the upper section B is a prop 37 which carries at its lower end a member 38 slidably and non-detachably engaged with the prop members 24 and 25. This construction, it will be obvious, will permit adjustment of the prop 37 in harmony with adjustment of the member B of the ladder. The prop member 37 also carries at its lower end a toothed plate 39 with which coöperates a pawl 40 in the form of a bail and pivotally connected to the prop members 24 and 25. The coöperation of this pawl 40 with the teeth of the plate 39 is effected by gravity and in order to disengage the pawl 40 from the plate 39 when desired I provide on said pawl an arm 41 to which is secured a flexible connection 42, the latter being adapted to be carried to any desired 40 point where it may be conveniently pulled to disengage the pawl 40 from the plate 39 and thus permit descent of the prop 37. In other words any tendency of the prop 37 to descend is prevented by engagement of the 45 pawl 40 with the tooth plate 39 and any tendency of the section B of the ladder to descend is prevented by the pawl 22 engaging one of the rungs 12 of the section A of the ladder.

50 In Figs. 7 to 9 I have shown my improved prop base associated with a non-extensible ladder embodying a ladder member D and a prop E pivoted thereto. The lower end of the prop E has secured to its inner and outer faces plates 43 between which is pivoted the prop base 44. This base also carries a notched segment 45 which is guided in its

movement by an eye member 46 carried by the prop. A spring controlled pawl 47 for engaging in the notches of the segment 45 60 is pivoted on the prop E and serves to secure the base in any desired adjustment to the prop. The pawl 47 is adapted to be disengaged from the notches of the segment 45 through the medium of a flexible pull member 48.

While I have illustrated and described one form of carrying my invention into practice it will be obvious that various changes in the details of construction and 70 the arrangement and combination of parts can be resorted to without departing from the scope of the invention as set forth in the appended claims.

What I claim is:

75 1. In an extension ladder, the combination of upper and lower ladder sections, props pivotally connected to said sections respectively and having slidable connection with each other, and means for securing the prop of the upper section against sliding movement downwardly with respect to the prop of the lower section.

2. In an extension ladder, the combination of upper and lower ladder sections, a prop pivotally connected on the lower section, a prop pivotally connected on the upper section, a member carried by the prop of the upper section and slidably engaged with the prop of the lower section, and detachable latching means for holding the prop of the upper section against movement downwardly with respect to the prop of the lower section.

3. In an extension ladder, the combination of upper and lower ladder sections, a prop pivotally connected on the lower section, a prop pivotally connected on the upper section, a member on the prop of the upper section slidably engaged with the prop of the lower section, a tooth member carried by the prop of the upper section, and a pawl pivoted on the prop of the lower section detachably engageable with the tooth member to hold the prop of the upper section 100 against movement downwardly with respect to the prop of the lower section.

105 In testimony whereof I affix my signature in the presence of two witnesses.

ELLSWORTH NICCUM.
